UNITED STATES PATENT OFFICE.

PATRICK J. MULVEY, OF BIRMINGHAM, ALABAMA, ASSIGNOR OF THREE-FIFTHS TO EDWARD H. PIGUE, OF NASHVILLE, TENNESSEE.

SECTIONAL BOILER.

SPECIFICATION forming part of Letters Patent No. 760,548, dated May 24, 1904.

Application filed November 5, 1903. Serial No. 179,970. (No model.)

To all whom it may concern:

Be it known that I, PATRICK J. MULVEY, a citizen of the United States, residing at Birmingham, in the county of Jefferson and State 5 of Alabama, have invented new and useful Improvements in Sectional Boilers, of which the following is a specification.

My invention relates to improvements in sectional boilers for use in connection with 10 steam and hot-water heating systems, and has for its object to increase the efficiency of the boiler by a novel construction and arrangement of parts which will cause the products of combustion as they pass to the exit-flue to 15 exert their influence against those parts of the boiler where they will promote the proper circulation of the water and act most rapidly to superheat or vaporize it.

With these objects in view I provide the 20 several sections with abutting water-legs forming the side and top walls of the boiler and with water-arches communicating with the side and top portions of the water-legs and provided with deflector-flanges which direct 25 the products of combustion after they have passed up between and through said arches against the center of the top of the boiler, so that the greatest heat is applied directly where it can be best utilized. The products are then 30 directed toward either side of the boiler and pass over the water-arches and downwardly into flues formed between the arches and side walls of the water-legs, through which they pass to the stack.

35 My invention comprises various other improvements in the construction and arrangements, which will be hereinafter more particularly described, and pointed out in the claims, reference being had to the accompanying 40 drawings, in which—

Figure 1 is a front elevation of the boiler. Fig. 2 is a transverse vertical section through the boiler along the line $x-x$ of Fig. 3. Fig. 3 is a longitudinal horizontal section through 45 the boiler along the line $y-y$ of Fig. 2. Fig. 4 is a plan view of one of the sectional damper-plates. Fig. 5 is a sectional view through a series of these damper-plates, showing the damper therein. Fig. 6 illustrates the inter-

locking top ends of the sections. Fig. 7 is a 50 perspective view of a half-section.

Similar reference-numerals refer to the same parts throughout the several figures.

The boiler, as illustrated, comprises a hollow front or end section 1, having the ash-pit door 55 2, fuel-door 3, and flue-doors 4. Between the front and the back end section 5 are four intermediate and independent sections, which may consist of integral castings, but are preferably made in two pieces 6 and 7 similar in 60 shape and provided with overlapping flanged ends 8, with transverse central openings and interposed gaskets or slip-nipples 9 to insure water-tight connections between said openings, so that they collectively constitute a continuous cylindrical chamber 10 for water or steam from front to rear of the boiler. An upper fastening-bolt 11 for the sections passes centrally through this chamber and is engaged by nuts 12, which lock the parts securely together. 70

The sections 6 and 7 are hollow castings formed with water-legs 13, which constitute the inner side and top walls of the boiler. The outer sides of these sections form the outer 75 walls of the boiler. Inlet-pipes 14 for the water-supply enter the lower ends of the water-legs, where they are enlarged to form, with the adjoining sections, a continuous chamber 15. These pipes 14 preferably enter alternate sections on each side of the boiler. The extensions or shoulders 16 at the lower end of the sections have openings through which the lower connecting-bolts 17 pass for securing the sections together. By providing one side of each section with a rib 18 and the other side with a complementary groove 19 in which the rib of the adjacent section engages the parts will 80 form close interlocked joints and hold securely together. The water-legs of the parts 6 and 7 of each section are formed of equal width throughout and provided with water-arches 20 of less width, which project inwardly to a point adjacent to each other and the vertical center of the boiler immediately over the center of the combustion-chamber 21. These arches comprise a lower substantially horizontal hollow leg 22, communicating with the

90
95

water-leg 13 and with two vertical legs 23 and 24, which are connected at their upper ends by a leg 25. This leg 25 also communicates with the top of water-leg 13 by a tube or passage 26. All these parts of the water-arch being of less width than the sections 6 and 7 permit the products of combustion from chamber 21 to pass freely between and around them, so that they are exposed directly to the heat on all sides. In order to direct these products so that they will exert their greatest influence against the top of the boiler, I provide the outer edges of members 25 and 26 and that portion of 22 between 26 and the water-leg 13 with side flanges 25^a and 22^a, respectively, of equal width with the sections, so that when in an assembled position they abut against each other and form deflector-walls which cause the products to pass upwardly through legs 22, 23, and 24 until they reach the leg 25, when the upper deflector-flanges 25^a cause them to pass around the inner end of the arch and impinge directly against the center of the top of the boiler. At this point the inner ends of the top sections of the water-legs 13 meet each other, forming a flat continuous inner top surface, and are provided with arched vertically-disposed extensions 27, forming the steam-dome, which communicate with the chamber 10. According to the construction described the water circulates from the passages 15 upwardly through the water-legs and branching therefrom through the legs 22, 23, and 24 and the tube or passages 26 to the top water-leg and thence upwardly through the extension 27 to the common chamber 10. The water will be gradually heated as it rises until it reaches the center of the top water-legs, when it will be at its maximum heat, and with a view to directing the products of combustion so that they will exert the greatest influence at the point where the water is most highly heated they are caused by the deflector-plates to pass straight to the under side of the top of the boiler, where they transform the water into steam or superheat it much more rapidly than if the heat were indirectly applied to the water or first to the cooler portion of the water-legs, as is the case in many boilers. The heated gases are deflected along under the top water-legs and above the legs 25 of the water-arches and around the passages 26 and enter the side flues 28 and 29, formed by the legs 24 and their abutting flanges 24^a and the side walls 55 of the water-legs 13 above flange 22^a. These flues lead longitudinally of the boiler, and the products of combustion pass through them and enter the branch pipes 30, leading from the rear end of the boiler to the stack. By this arrangement it will be seen that the outer or cooler sections of the boiler are subjected to proportionately less heat, which will cause the water to circulate naturally from the water-legs through the arch toward the chamber 10, which represents the steam-arch, and to

return through the top and upper side water-legs 13.

In order to control the flow of the products of combustion and regulate the boiler, I provide a series of damper-plates 31, which rest on lugs 32 on sides of water-legs 24 and 13 near the top of the flues 28 and 29. These damper-plates conform in shape with the opening between the said water-legs and are so arranged that when the boiler-sections are assembled they form continuous plates provided with openings 32 at regular intervals, over which the dampers 33 are moved by rods or handles extending through the front section of the casing. The dampers have dependent lips or tongues 34, which enter these openings 32 and serve the purpose of cleaning them of soot or sediment and regulate the throw of the dampers. By moving either damper to its closed position one side of the boiler will be practically out of operation and the heating capacity of the boiler greatly reduced. It will be noted that when the products of combustion are directed toward one side of the boiler exclusively there will be free circulation of water in the arches 20 through the legs 23, 25, 24, and 22, which will prevent any unequal heating of the water in the water-arches.

By directing the products of combustion from the fire-chamber 21 directly to the center of the top of the boiler and then forcing them to divide and pass along the inner walls of the boiler formed by the water-legs 13 until they reach the flues 28 and 29, through which they pass to the stack, I secure from them their greatest heating capacity without interfering with the draft, and at the same time the most natural and effective circulation of water results.

The grate-sections 35, which rest upon the bars 36, may be of any desired construction, and these bars may be also used to support the several sections of the boiler.

The back 5 of the boiler is hollow and constitutes the usual water-jacket or end, while the front is also formed hollow in the usual manner. Suitable well-known connections between the front and back and the circulating-sections are formed.

Having thus described my invention, what I claim as new, and desire to secure by Letters Patent, is—

1. A steam boiler or heater consisting of sections joined and formed with abutting side and top water-legs, water-arches communicating with said side and top sections of the water-legs and forming with said sections deflecting-passages for the products of combustion, which force them to pass directly to the center of the top water-legs and then over said arches and enter an exit-flue formed between said arches and the side water-legs.

2. A steam boiler or heater, a series of joined sections serving as water-legs, series of

inwardly-disposed projections through which the water circulates from said legs, and deflector-partitions forming passages lengthwise of the boiler leading between and over said projections and said passages opening into a longitudinal flue on each side of the boiler formed between said projections and the side water-legs.

3. In a sectional boiler a series of transversely-disposed sections, each of which comprises side and top water-legs and inwardly-disposed water-arches connected to each side water-leg and the top water-leg, said arches being of less width than said water-legs and provided with deflector-flanges which direct the products of combustion between and over said arches, and form horizontal exit-flues between the flanged sides of said water-arches and the adjacent side water-legs.

20 4. In a sectional steam-boiler, a series of transversely-disposed water-sections formed in two parts suitably connected at the top of the boiler and communicating with a horizontal chamber, and with water-arches which project inwardly to a point adjacent to each other near the vertical center of the boiler, abutting flanges on the top and outer side of said water-arches which form with the top and side water-legs transverse horizontal passages and 30 side flues, and means to regulate the flow of the products of combustion from said passages into said flues.

5. In a sectional steam-boiler, a series of two-part sections provided with overlapping communicating shoulders at their upper ends and formed with side and top water-legs, an inwardly-disposed water-arch communicating with the water-leg of each part and formed with horizontal and vertical communicating 35 legs and deflector-flanges, on said horizontal and vertical legs of said arches forming longitudinal central top and side flues and directing the products of combustion against the longitudinal center of the top of the boiler 40 before they enter said flues.

6. In a sectional boiler, outer water-legs and inwardly-disposed water-arches communicating with said legs, top and side horizontal flues formed between said arches and said 50 legs, and horizontal damper-plates forming a continuous apertured partition between said top and side flues, and dampers opening or closing said aperture.

7. In a sectional boiler, a series of joined sections comprising water-legs forming the casing and inwardly-disposed water-arches forming side and top horizontal passages between them and said casing, and sectional damper-plates of equal width with said sections and disposed to form a continuous par-

55 tition, and a damper movable over said partition.

8. In a sectional boiler, a series of sections formed with water-legs constituting the casing of said boiler, inwardly-disposed water-arches leading from inner sides of each section, said water-arches being arranged relative to each other, so that the products of combustion pass between and through them and are deflected by abutting portions so that 70 they pass between the inner and upper ends of the oppositely-disposed arches at a point adjacent to the central portion of a top water-leg and thence under the top of the boiler before passing to their exit flue or flues.

75 9. In a sectional boiler, a section comprising side and top water-legs and oppositely-disposed water-arches communicating therewith and arranged relatively to the arches of adjacent sections so that the products of combustion pass between and through said arches directly to the top water-legs and thence over the tops of said arches and enter flues formed by the rear walls of said arches and the sides of the boiler.

80 10. In a sectional boiler, a section comprising side and top water-legs and a water-arch formed of four communicating water-legs which constitute a substantially rectangular frame, connections leading from the lower 90 and upper portions of said water-arch to a side and top water-leg respectively of said section and a flange leading around the two water-legs of the arch adjacent to the side and top water-legs.

85 11. In a sectional boiler, sections comprising side and top water-legs, water-arches, and flanges on said arches which abut and form a longitudinal central flue which directs the products of combustion between said arches 100 and against the center of said top water-legs before they have access to said side water-legs.

95 12. In a sectional boiler, sections comprising two water-legs and overhanging water-arches, a top water-leg and steam-arch, and inverted-L-shaped abutting flanges on said water-arches which force the products of combustion to pass directly from the grate to the steam-arch, and which form top and side flues 110 into which the said products are deflected after impinging against said steam-arch and from which they pass to the exit-flue.

115 In testimony whereof I have signed my name to this specification in the presence of two subscribing witnesses.

PATRICK J. MULVEY.
